WILLIAM P. UHLINGER, OF PHILADELPHIA, PENNSYLVANIA.

Design No. 4,068, dated May 24, 1870.

DESIGN FOR A SCHOOL-DESK.

The Schedule referred to in these Letters Patent and making part of the same

To all whom it may concern:

Be it known that I, WILLIAM P. UHLINGER, of Philadelphia, in the county of Philadelphia and State of Pennsylvania, have invented a new and valuable Design for School-Desks; and I do hereby declare that the following is a full, clear, and exact description of the same, reference being had to the annexed drawing making a part of this specification.

Figure 1 of the drawing represents an external view of my school-desk, with the seat turned down, and

Figure 2 is a similar view, with the seat folded up.

What I claim as my invention, and desire to secure by Letters Patent, is—

The design of the combined school-desk and seat, as shown in the drawing herewith.

In testimony that I claim the above, I have hereunto subscribed my name in the presence of two witnesses.

W. P. UHLINGER.
